UNITED STATES PATENT OFFICE.

CHARLES L. RAYFIELD, OF CHICAGO, ILLINOIS, ASSIGNOR, BY MESNE ASSIGNMENTS, TO MARVEL CARBURETER COMPANY, OF FLINT, MICHIGAN, A CORPORATION OF INDIANA.

FLOATING-VENTURI CARBURETOR.

Application filed September 15, 1920. Serial No. 410,403.

This invention relates to a carburetor, and particularly to a carburetor wherein the Venturi mixing chamber is automatically adjustable in such a manner that the proper fuel mixture is at all times supplied to the engine on which the carburetor is mounted.

In the design of carburetors, fuel economy and smoothness of operation are features which must be given paramount consideration. These results are obtained by mixing the fuel and air in such proportions in the carburetor that a maximum explosive effort is produced when the mixture is ignited in the engine cylinder. Varying conditions of load and feed, however, require that the proportions and quantities of fuel mixture be constantly varied.

It is therefore desirable that a carburetor be provided which will supply the proper quantities of fuel mixture for varying conditions of feed and load and that it be automatically adjustable to supply this mixture promptly and in sufficient quantities as the demand therefor arises.

It is an object of this invention to provide a carburetor having a plurality of throttle controlled mixture adjusting means.

It is also an object of this invention to provide a carburetor having throttle controlled mixture adjusting means and having suction controlled mixture adjusting means associated with certain of said throttle controlled means.

It is a further object of this invention to provide a carburetor having fuel injecting means adapted to be brought into operation by the opening of the throttle thereof.

It is an important object of this invention to provide a carburetor having a plurality of nozzles certain of which are brought into operation by opening the throttle of the carburetor.

It is also an important object of this invention to provide a carburetor having a casting affording a Venturi mixing chamber, said casting being movable to admit additional fuel mixture on the outside thereof.

It is finally an important object of this invention to provide a carburetor having a plurality of coacting throttle controlled and suction operated means for varying the fuel mixture.

Other and further important objects of this

invention will be apparent from the disclosures in the specification and the accompanying drawings.

The invention (in a preferred form) is shown on the drawings and hereinafter more fully described.

On the drawings:

Figure 1 is a side elevation of a carburetor embodying the principles of this invention.

Figure 2 is an elevation of the opposite side thereof.

Figure 3 is an end elevation.

Figure 4 is a section on the line 4-4 of Figure 3.

Figure 5 is a plan view.

Figure 6 is a section on the line 6-6 of Figure 5.

Figure 7 is an enlarged fragmentary section on the line 7-7 of Figure 2.

Figure 8 is a section on the line 8-8 of Figure 2.

Figure 9 is an enlarged fragmentary section on the line 9-9 of Figure 4.

Figure 10 is an enlarged fragmentary section on the line 10-10 of Figure 4.

Figure 11 is a slightly enlarged section on the line 11-11 of Figure 6.

Figure 12 is an enlarged fragmentary section on the line 12-12 of Figure 6.

Figure 13 is an enlarged fragmentary detail section of the liquid fuel inlet.

Figure 14 is a fragmentary vertical section through the liquid dash-pot chamber and the piston operating therein.

Figure 15 is an enlarged section on the line 15-15 of Figure 14.

Figure 16 is an enlarged fragmentary section with parts in elevation on the line 16-16 of Figure 5.

As shown in the drawings:

The carburetor of this invention comprises in general a unitary casing in which is formed a float or fuel supply chamber 1, an air inlet passage 2 and a mixing chamber 3, the outlet of fuel from which is controlled by a butterfly throttle valve 4. As shown in Figures 6 and 13, liquid fuel enters the chamber 1, through a chambered boss 5, to which a pipe from the source of fuel extends, through a passage in the bottom of the casing from which the supply chamber is formed, and into said chamber 1 through passages 6 in a hexagonal nut 7,

which is an integral part of a plug 8 engaged in the passage in the casing. A needle valve 9, in the passage in said plug 8, controls the flow of liquid fuel through the passages 6, 7 and said needle valve 9 is controlled by a float 10 in the usual manner to maintain a constant level in the chamber 1. Centrally mounted in the air inlet passage 2 is a vertical stand pipe 11, the upper end of which is closed by a plug 12, which has a plurality of holes 13 drilled therein to provide an outer fuel nozzle. Secured inside said standpipe or tube 11 is a second tube 14, the external diameter of which is slightly less than the internal diameter of the tube 11, thereby affording a passage 15 between said tubes. A connection between said passage 15 and the interior of the tube 14 is provided by the restricted passage 15'. For closing the upper end of tube 14 a metering pin 16 is provided and said metering pin is adapted to be moved outwardly in said tube to allow liquid fuel to be drawn therefrom, thereby providing an inner nozzle. An extension 16' on said metering pin 16 projects downwardly through the tube 14, into a well 17, which is formed in the carburetor casing directly beneath the air inlet passage 2, and said extension 16' is connected to a piston 18, which is slidably mounted in said cylindrical well 17. As shown in Fig. 14, said piston 18 is provided with vertical passages 19 and with a check valve 20, which is loosely secured on the extension 16' of the metering pin 16, and by this arrangement said piston is adapted to move easily downward through the liquid in the well 17, but its upward movement therethrough is restricted since the check valve 20 closes over the passages 19 due to its weight. Slidably mounted in the carburetor casing above the air inlet chamber 2 is a casing 22, in which is centrally formed a Venturi chamber 23 which surrounds the upper end of the stand pipe or tube 11. As shown in Figure 4, said casing 22 is provided with a plurality of outwardly extending fins 24, which are adapted to slidably engage the side of the carburetor casing and afford a passage between the casing 22 and the inside of the carburetor casing. An annular boss 25, which is formed on the outside of the casing 22, near the lower end thereof, is adapted to engage an annular flange 26 formed in the carburetor casing at the upper end of the air inlet chamber 2, and thus close the connection from said air inlet chamber to the passages formed between the fins 24 and the outside of the casing 22, and the inside of the carburetor casing. To restrict the entrance of air into the Venturi chamber 23, a double cone 27 is secured around the tube 11, adjacent the entrance to said chamber, as clearly shown in Figure 6. Said cone 27 may be made adjustable by internally threading the same and by threading the outside of the tube 11 to engage

the same. It is apparent from the preceding description that the construction of this invention provides in effect a floating venturi. Upon the production of increased suction due to a high or increased engine speed, the 70 casing 22 will be lifted upwardly and the boss 25 moved away from its seat on the flange 26, thus allowing an additional passage for the flow of air into the fuel outlet chamber 3.

Means are provided whereby the metering 75 pin 16 is moved upwardly in the tube 14 by the upward movement of the casing 22, thereby admitting a certain quantity of additional fuel through the inner nozzle when additional air is admitted around the casing 22. For 80 this purpose, inwardly extending arms 28 are provided near the upper end of the casing 22 and said arms extend to the center of the upper end of the Venturi chamber 23, where they are loosely engaged between flanges of 85 an internally threaded boss 29, which is engaged on threads on the upper end of said metering pin 16. A plate 30 adjustably secured on the pin 16 below the boss 29 deflects the fuel in its upward course and acts to 90 thoroughly mix the same, adding to the economy of the carburetor. Since said plate 30 moves away from the nozzle at high speeds and towards the same at lower speeds, the deflecting effect thereof is properly compensated. Thus it is apparent that an upward movement of the casing 22 is transmitted to the metering pin moving the same outwardly in the tube 14 and allowing fuel to flow therepast from the interior of said tube. Since 100 the piston 18, which is movable in the liquid in the well 17, is connected to the lower end of said metering pin, the upward movement thereof with the casing 22 is retarded by the resistance offered by the liquid in said well, 105 while at the same time, on account of the provision of the check valve 20 and the passages 19 in the piston 18, the casing 22 and the metering pin are quickly dropped back into position when the suction which lifted the 110 same upwardly ceases. In this connection, it is to be noted here that the upper end of the well 17 is closed by an outwardly extending flange 31, which is provided on the lower end 115 of the tube 14.

Means are provided for supplying liquid fuel to the well 17 and to the interior of the tubes 11 and 14. For supplying the well 17 with liquid fuel, a passage 32 is provided in the carburetor casing opening into said well 120 and said passage communicates with another passage 33, which in turn communicates with a vertical passage 34, communicating with a well 35, which is supplied with liquid fuel from the float chamber 1 through a passage 125 38, as clearly shown in Figure 7. Said well 35 with the vertical passage 34 leading thereto is shown in Figure 9. Liquid fuel is supplied to the interior of the standpipe tube 11 by means of a passage 36, which connects 130

with the lower end of the chamber 15 between said tube 11 and the tube 14, said passage 36 in turn communicating with passages 37 and 38 and a vertical passage 39 which opens into a well 40 communicating with float chamber 1 through a restricted passage 89 (Figs. 7 and 10). Said wells 35 and 40 are respectively formed in bosses 41 and 42 on the side of the carburetor casing as clearly shown in Fig. 2, and the flow of fuel therefrom into the passages 34 and 39 is regulated by needle valves 43 and 44, which are slidably mounted in said passages and adapted to be seated and unseated by the closing and opening of the throttle in a manner which will now be described.

A passage 100 in the casing 42 affords an atmospheric connection to the top of the well 40 and since the passage 89, which supplies liquid fuel thereto from the chamber 1, is restricted by an apertured nut 89^a, Fig. 7 the supply of liquid fuel will be drawn therefrom upon initial acceleration of the engine. After the exhaustion of the liquid fuel in said well 40 and during continued running at high speeds, air will of course be induced through the passage 100 and supplied to the carburetor nozzle through the passage 36. Said well 40 will be again filled with liquid fuel through the restricted passage 89 upon stopping or slowing down the engine.

The butterfly throttle valve 4 is secured on a shaft 45, which is pivoted transversely in the carburetor casing in the mixture outlet chamber 3 thereof in the usual and well-known manner and on the outer end of said shaft 45 is secured an eccentric cam 46, which rotates with the shaft 45 when the throttle is opened or closed to contact with a roller 47 which is mounted on one end of a bell crank rocker arm 48, which is pivoted to the outside of the carburetor casing at 49. The other end 50^a of the rocker arm 48 is bifurcated and extends outwardly to engage under a fork 50, which is provided with a threaded aperture to receive a threaded portion 51 on the upper end of the needle valve 43. Said fork 50 is also adapted to contact a knurled nut 52, which is secured to the upper end of the needle valve 44, and to lift said valve upwardly away from its seat when the throttle is moved into open position. It is to be noted, however, that the fork 50 acts to move the needle valve 43 at any time the rocker arm 48 is moved while the needle valve 44 is not moved until after considerable rocking movement of said rocker arm has been effected, as for example, when the throttle is opened at half to three-quarters open position. Said knurled nut 52 also provides means whereby the needle valve 44 may be adjusted longitudinally in the casing 42. Means are also provided for adjusting the needle valve 43 longitudinally and for this purpose a knurled nut 53 is secured to the upper end of said needle

valve whereby the same may be rotated in its threaded aperture in the fork 50 to adjust its position relative to the fork 50. In order to lock said knurled nut 53 in adjusted position, a spring-pressed detent 54 is provided and a similar spring-pressed detent may also be provided for locking the knurled nut 52 in adjusted position.

An auxiliary nozzle is provided for supplying at all times a limited amount of fuel mixed with air to the mixing chamber 3 from a point above the annular flange 26. For this purpose a passage 55 leading into the well 35 conducts liquid fuel to a well 56 formed in a casing 57 on the same side of the carburetor casing as the rocker arm 48. Mounted in the upper end of said well 56 is a restricted nozzle 59 and a constant air port 58 in the casing 57 supplies air to the fuel leaving the upper end of said nozzle. The auxiliary nozzle serves to supply a substantially uniform quantity of fuel, sufficient to form a properly explosive mixture with the air flowing through the venturi when the venturi is seated on the flange 26.

In order to provide for easy starting and for a supply of fuel mixture when the engine is idling, an arrangement is provided for supplying fuel mixture to the mixing chamber 3 at a point posterior to the throttle valve 4. This arrangement is shown in Figures 1, 3 and 16 and comprises a casing 60, which is provided with a plurality of passages which communicate with the float chamber 1 by means of a passage 61. A horizontal passage 62 in said casing 60 communicates with a vertical passage 63 therein and the upper end of said vertical passage is closed by a plug 64, which has a restricted passage 65 therein affording an auxiliary nozzle. A second passage 66 leads upwardly from the horizontal passage 62 to a cylindrical chamber 67, in which a valve 68 is rotatably mounted for selectively connecting said chamber 67 either with said passage 66 or with the atmosphere through a vertical passage 69 leading from said cylindrical chamber. Leading upwardly from the cylindrical chamber 67 is a passage 70 which opens into a passage 72 in a casing 71 which is secured to the top of the main casing and which is provided with an aperture 73 into which the plug 64 extends. For regulating the flow of air or fuel through said passage 72, a valve 74 is engaged in the outer end thereof and is adapted to be adjusted therein by rotating a threaded portion 75 thereon in a threaded portion 76 of the casing 71. For rotating said valve 74, the outer end of the threaded portion 75 is provided with a knurled head 77, as clearly shown in Figures 1 and 16. Thus it is apparent that fuel leaving the passage 65 in the plug 64 is mixed with air from the passage 70 in the passage 72, the valve 74 being cut away as shown to allow free passage of this mixture thereabout and

from this passage 72 the fuel mixture is drawn upwardly through a passage 78 into a circular passage 79, which is formed between a bushing 80 surrounding the throttle shaft 45 and a portion of the casing 71. From said cylindrical passage 79 the fuel is drawn upwardly and inwardly through passages 81 and 82 into the mixing chamber 3 at a point above the throttle valve 4. Thus provision is made for supplying mixture to run the engine idly when the throttle valve 4 is in closed position.

In order to facilitate starting, means are provided whereby a very rich mixture may be introduced through the passage 82. To accomplish this result the cylindrical valve 8 is rotated so that the air inlet passage 69 is closed and so that the chamber 72 is connected only with the liquid fuel passage 62. In order that said valve 68 may be rotated into the desired position for starting the engine or for running idle, an extension 83 thereof is brought outwardly through the casing 60 and a lever 84 is non-rotatably secured to the outer end of said extension. Said lever 84 is provided with a binding post 85, whereby a rod or Bowden wire may be attached thereto so that the lever may be operated from a distance to rotate the valve 68. An extension 86 is provided on the end of said lever 84 opposite the binding post 85 and a stop 87 which is adapted to be engaged by said extension 86 and by the lever 84 limits the movement of said lever in both directions so that it is possible to readily ascertain when the valve 68 is rotated into the desired position.

Any suitable means may be provided for rotating the throttle shaft 45, such as a rocker arm 90, as shown in Figure 3.

The operation is as follows:

The float chamber is filled with liquid fuel which enters the same through the boss 5 and the level in said float chamber is maintained in the usual manner by the action of the float 10, and the needle valve 9 controlled thereby. When it is desired to start the engine, the lever 84 is actuated to rotate the valve 68 in such a manner that the air passage 69 is closed and consequently a very rich mixture or practically raw fuel is drawn into the mixing chamber 3, above the throttle 4. After the engine has started the lever 84 is of course moved back to its original position so that the liquid fuel passage 66 is closed and the air passage 69 is again opened and a properly proportioned mixture of air and liquid fuel enters through the passage 82. This mixture, which is introduced through the passage 82, suffices to idle the engine when the throttle valve 4 is closed and the operation of the carburetor which takes place upon opening said throttle valve will now be described.

Upon opening of the throttle the nozzle 59, which is supplied with air from the constant air inlet 58, supplies primary mixture to the

mixing chamber 3, said fuel mixture being drawn thereto by aspiration. The opening of the throttle also causes the cam 46 on the throttle shaft 45 to contact with the roller 47 and to rock the rocker arm 48 about the pivot 49 whereby the needle valve 43 is lifted from its seat and the additional fuel required is allowed to flow into the well 17 through the passages 34, 33 and 32. The valve 43 is sufficiently opened at all times to allow a limited flow of fuel into the well 17. The fuel from said well 17 rises upwardly inside the tube 14 and is drawn out through the apertures 13 into the Venturi chamber 23, where it is mixed with air from the air inlet chamber 2. Said fuel which is drawn into the mixing chamber through the apertured passages 13 enters the chamber 15 between tubes 11 and 14 through a restricted passage 15^a formed in the tube 14, and therefore the amount of fuel drawn through said aperture is limited. As the speed of the engine increases the suction produced thereby lifts the casing 22 so that the boss 25 thereon is lifted away from the flange 26 and additional air from the air inlet chamber 2 is drawn upwardly between the fins 24 on said casing 22. This upward movement of the casing 22 moves the entrance to the Venturi chamber 23 away from the cone 27 and consequently increases the size of the opening 95 thereinto and increases the amount of air which may be drawn therethrough. On account of the action of the piston 18 in the well 17, this upward movement of the casing 22 is a gradual one so that the acceleration of the engine effected thereby is smooth and steady. The additional air which is introduced by the lifting of the casing 22 requires additional fuel and this is provided for by the outward movement of the metering pin 105 16 in the tube 14, which permits liquid fuel to be drawn from said tube. This action, however, is a compensating one and prevents the "loading" effect often caused by such conditions.

Means are also provided for introducing additional fuel at high speed or when the throttle is in open position. After the throttle has been moved to about half to three-quarters open position, the fork 50 has been lifted by the rocker arm 48 sufficiently to contact with the bottom of the knurled nut 52 on the needle valve 44, raising the same from its seat in the bottom of the well 40 and momentarily supplying additional liquid fuel 115 to the chamber 15 through the passages 39, 38, 37 and 36. After the exhaustion of the fuel in the well 40, air is induced through the passage 100 into said passages. Thus at high speed there are a plurality of jets in operation. Fuel is supplied through the apertures 13 in the top of the tube 11, from the nozzle formed between the metering pin 16 and the top of the tube 14, from the nozzle 59 and from the passage 82 which communicates with the

nozzle 64. On account of the sliding movement of the casing 22, the proper amount of air is supplied at all times and the compensating movement of the casing 22, together with the throttle controlled liquid fuel supply, provides an arrangement whereby the proper fuel mixture is promptly supplied for all running conditions. On account of the provision of the check valve 20 the casing 22 is allowed to drop quickly back so that the boss 25 thereon seats on the flange 26 when the speed is diminished and the suction ceases. Thus while the upward movement of said casing is made smooth and gradual by the action of the piston 19, there is no lag in its movement back to normal position upon cessation of suction. Adjustments which may be necessary for the proper proportioning of the fuel mixture may conveniently be made. Adjustment of the needle valves 43 and 44 is effected by rotating the knurled nuts 52 and 53, adjustment of the air supply through the nozzle 64 is effected by rotating the knurled nut 77, and adjustment of the air inlet into the Venturi chamber 23 is ordinarily made when the carburetor is assembled by adjusting the double cone 27 longitudinally on the sleeve 11. As is apparent from the foregoing description, the carburetor of this invention provides means whereby a properly proportioned mix-

ture is supplied to the engine under all running conditions and means whereby this mixture is compensatingly proportioned by means dependent both upon suction and upon the amount of throttle opening.

I am aware that numerous details of construction may be varied through a wide range without departing from the principles of this invention, and I therefore do not purpose limiting the patent granted otherwise than necessitated by the prior art.

I claim as my invention:

1. In a carburetor, a fuel supply chamber, a plurality of wells communicating therewith, a compound nozzle communicating with said wells, means for controlling the flow of fuel from said wells to the nozzle, and throttle controlled means for successively operating said controlling means.

2. In a carburetor, a fuel supply chamber, a plurality of wells communicating therewith, a compound nozzle, a separate communication from each of said wells to the nozzle, and throttle controlled means in each of said wells, said means successively controlling the flow of fuel therefrom to the nozzle.

In testimony whereof I have hereunto subscribed my name.

CHARLES L. RAYFIELD.
